US00D516545S

(12) **United States Design Patent** (10) Patent No.: **US D516,545 S**
Lai (45) Date of Patent: **** Mar. 7, 2006**

(54) **LASER REMOTE CONTROL DEVICE**

(75) Inventor: **Jung-Hua Lai**, Yonher (TW)

(73) Assignee: **King Wins Technology Co., Ltd.**,
Yonher (TW)

(**) Term: **14 Years**

(21) Appl. No.: **29/220,548**

(22) Filed: **Dec. 30, 2004**

(51) LOC (8) Cl. **14-03**

(52) U.S. Cl. **D14/218**

(58) Field of Classification Search **D14/174, D14/217, 218, 137-139, 151, 191-193, 299, D14/167, 168; D13/168, 162-164; D21/512-517, D21/566; D10/104, 106; 455/352-355, 151.1-151.4, 455/128, 347, 90.3; 348/114, 734**

See application file for complete search history.

(57) **CLAIM**

The ornamental design for a laser remote control device, as shown and described.

DESCRIPTION

FIG. 1 is a perspective view of a laser remote control device showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.
